UNITED STATES PATENT OFFICE.

CARL A. JOERISSEN, OF WASHINGTON, DISTRICT OF COLUMBIA.

TYPE-WRITING MACHINE.

No. 911,014.

Specification of Letters Patent.

Patented Jan. 26, 1909.

Application filed May 28, 1908. Serial No. 435,387.

To all whom it may concern:

Be it known that I, CARL A. JOERISSEN, a citizen of the United States, residing in the city of Washington, District of Columbia, 5 have invented certain new and useful Improvements in Type-Writing Machines, of which the following is a specification.

This invention relates to the type bar segments of writing machines having detachable 10 type bars.

The principal object of the invention is to render it feasible to take out and replace individual bars without the necessity of constructing the type bar in such a manner that 15 it is liable to become accidentally displaced from its position on the segment.

The principal feature of the invention consists in providing recesses at intervals along 20 a fulcrum rod upon which the type bars are mounted, the recesses corresponding to the intervals at which the type bars are placed in the segment. The type bars have open slots, the openings in the slots being too 25 small to permit them to pass over the body of the fulcrum rod, while sufficiently large to pass over the slotted or recessed portions of the fulcrum rod. The latter may be moved endwise to secure the bars after they have been placed thereon.

30 In the accompanying drawings, Figure 1 is a rear elevation of the type bar segment showing the fulcrum rod in position for attachment of the type bars thereto. Fig. 2 is a sectional side elevation of the type bar 35 and segment. Fig. 3 is a view similar to Fig. 1, but showing the fulcrum rod moved into position to lock the type bars, and there secured by a screw. Fig. 4 is a view of the fulcrum rod. Fig. 5 illustrates the manner 40 of placing a type bar upon the rod. Fig. 6 is an enlarged view to show the proportions of the different parts of the rod and the opening in the type bar slot. Fig. 7 shows the rod recesses as beveled for the purpose of 45 camming or lifting the bars onto the un- recessed or body portions of the rod.

50 Bars 1 carrying types 2 are mounted in radial slots 3 formed in a segment 4, the bars striking rearwardly against a platen 5. The bars have slots 6, whereby they are fulcrumed upon a rod 7, the latter curved and seated in a groove 8 in the segment.

The bar is formed at intervals with recesses or cutaways 9, formed preferably on 55 both the concave and the convex sides of the rod, as shown; and every bar has an opening

10 into the slot 6, said opening too small to permit the bar to be slipped on or off the uncut body portion of the rod 7, see Fig. 6; but large enough to pass over any recessed 60 portion of the rod.

In assembling the type bars, the rod 7 is placed in the Fig. 1 position, and the bars all inserted in the slot 3. Then the bar 7 is moved endwise to the left, as at Fig. 3, so 65 that the body or uncut portions of the rod are engaged by the type bar slots 6; the recesses 9 occupying positions between the segment slots 3. It is now impossible for any bar to come off from the rod. The latter is 70 locked in its bar-locking position by means of a screw 11, the head of which catches upon the bar.

When it is desired to take out any bar, it is only necessary to loosen the screw 11, and 75 move the rod 7 to the right to the Fig. 1 position, when the bar may be readily slipped off.

If desired, the recesses 9 in the rod may be formed with beveled sides 12, to cam or lift 80 the bars onto the body portions of the rod 7, during the endwise movement of the latter. By reason of this bevel 12, it becomes impossible for the type bars by falling into the recesses 9, to lock the rod against endwise 85 movement.

Variations may be resorted to, as for instance the recesses 9 may be omitted on either the inner or the outer side of the rod 7, and the opening 10 made a trifle larger to 90 correspond.

Having thus described my invention, I claim:

1. In a typewriting machine, the combination with a series of type bars having open 95 slots, of a segment having radial slots to receive the type bars and having an endwise shiftable fulcrum bar for said type-bars; the fulcrum rod being formed with recesses, one for each type bar, at intervals corresponding 100 to the intervals between the segment slots; the opening in each type bar slot being too small to pass over the body of the bar, but large enough to pass over a recessed portion of the rod; whereby the bars may be assembled upon the fulcrum rod, and the latter may then be moved endwise to lock the type bars against accidental displacement.

2. In a typewriting machine, the combination with a series of type bars having open 110 slots, of a segment having radial slots to receive the type bars and having an endwise

- shiftable fulcrum bar for said type bars; the fulcrum bar being formed with recesses, one for each type bar, at intervals corresponding to the intervals between the segment slots; 5 the opening in each type bar slot being too small to pass over the body of the bar, but large enough to pass over a recessed portion of the bar; means being provided to lock the fulcrum rod in bar-locking position.
- 10 3. In a typewriting machine, the combination with a series of type bars having open slots, of a segment having radial slots to receive the type bars and having an endwise shiftable fulcrum bar for said type bars; the fulcrum rod being formed with recesses, one for each type bar, at intervals corresponding to the intervals between the segment slots; the opening in each type bar slot being too 15 small to pass over the body of the bar, but large enough to pass over a recessed portion 20 of the bar; the recesses in the fulcrum rod having beveled sides to enable the rod during its longitudinal movement to cam or lift the type bars onto the body portions of the rod.
4. A curved fulcrum rod for a system of 25 type-bars, recessed at intervals corresponding to the spacing of the bars from one another.
5. A curved fulcrum rod for a system of type-bars, recessed at intervals correspond- 30 ing to the spacing of the bars from one another; each recess formed with a bevel for the purpose specified.

CARL A. JOERISSEN.
